(74) Attorney, Agent, or Firm — Lavery, De Billy, LLP;
Gwendoline Bruneau(57) CLAIM

The ornamental design for a rake, as shown and described.

DESCRIPTION

FIG. 1 is perspective view of our new design shown with an unclaimed handle;

FIG. 2 is an enlarged front view thereof;

FIG. 3 is a left side view thereof;

FIG. 4 is a right side view thereof;

FIG. 5 is a top view thereof;

FIG. 6 is a bottom view thereof; and,

FIG. 7 is a back view thereof.

The broken lines in the figures depict portions of the rake that form no part of the claimed design.
